FIG. 1 is a front perspective view of a positive airway pressure delivery console according to our new ornamental design;

FIG. 2 is front view thereof;

FIG. 3 is a rear view thereof;

FIG. 4 is a top view thereof;

FIG. 5 is a left side view thereof; and,

FIG. 6 is another front perspective view thereof.

The broken lines represent environment or structure and do not form a portion of the claimed design.

One or more views (e.g., the bottom view) may be omitted and therefore does not form a part of the claimed design.
